CARL W. VOLLMANN, OF MONTREAL, QUEBEC, CANADA.

GAS-COMPRESSOR.

1,301,987.

Specification of Letters Patent. Patented Apr. 29, 1919.

Application filed February 2, 1918. Serial No. 215,222.

To all whom it may concern:

Be it known that I, CARL W. VOLLMANN, of the city of Montreal, Province of Quebec, Dominion of Canada, have invented certain new and useful Improvements in Gas-Compressors; and I do hereby declare that the following is a full, clear, and exact description thereof.

My invention relates to reciprocating compressors for compressing ammonia, carbonic acid and other gases; and has for its object to provide a direct acting compressor, that is to say, one involving a direct connection with the source of compressive force, the purpose being to obviate the use of a fly-wheel or other means extraneous to the compressor proper, for securing the travel of the piston to each end of the cylinder.

The invention may be said briefly to consist of a direct acting reciprocating compressor comprising a cylinder containing a reciprocating piston, and means contained within the cylinder for securing the travel of the piston to the ends of the cylinder. More specifically stated this means consists of a device whereby the unexpelled compressed gas contained in the end of the cylinder when the piston approaches that end, is transferred to the opposite or low pressure side of the piston, this transfer of the compressed gas being effected by a by-pass port. In order to obtain a high degree of efficiency from the compressor and to prevent the obstruction of the movement of the piston by any liquefied gas contained in the end of the cylinder which the piston approaches, I have arranged a particular design of valvular mechanism to, as it were, co-act with the by-pass ports and cause a sudden admission of steam into the engine cylinder during the transfer of the gas from one to the other side of the piston of the compressor. This co-acting valve gear comprises a valvular piston for operating the valve proper during the time that the gas is being transferred.

For full comprehension, however, of my invention, reference must be had to the accompanying drawings forming a part of this specification in which similar reference characters indicate the same parts and wherein:

Figure 1 is a side elevation of a gas compressing unit constructed according to my invention.

Fig. 2 is a detail plan view of the gas

compressing member of the unit and the direct connection between it and the power developing member.

Fig. 3 is a sectional view taken on line 3—3 Fig. 2.

Fig. 4 is a detail sectional view of the valvular mechanism of the power developing member.

Fig. 5 is a sectional view taken on line 5—5 of Fig. 4.

Fig. 6 is a detail sectional view taken on line 6—6 Fig. 5; and

Fig. 7 is a sectional view taken on line 7—7, Fig. 6.

The source of compressive force in the preferred embodiment of my invention, illustrated in the drawings, comprises a steam cylinder *b*, and a gas cylinder *c*, in which compression takes place these cylinders containing pistons *e* rigidly connected together to work in unison by their piston rods *f* and *g* which are united by a coupling *h*. The steam cylinder is of usual approved construction and design suitable for developing the power necessary to operate the compressor with which it is coupled, a slide valve *k* being employed and a specific operating gear is arranged to operate the valve while the compressor piston is completing its stroke. I will describe the compressor mechanism, however, before describing the detail construction and arrangement of this valve gear.

The cylinder of the compressor has cylinder heads *l* and *m* respectively each having a hub or boss *n*, and the head *m* has an integral sleeve *o* with stuffing box *p*, the sleeve containing a gland *r* and having a lubricating hole *s*, see Fig. 3. The steam cylinder or engine and compressor are rigidly connected together by having their cylinder heads *m* and *i* connected up by a rigid yoke consisting of a pair of arms *u* and *v* preferably cast in one piece with the cylinder heads and the sleeve *o*. The members of the unit being further bound together by a base *w* and a pair of box like legs *x* and *y* cast in one with the cylinders of the power developing and gas compressing members, such legs being bolted to the base.

The gas supply pipes are coupled to inlet valves 10 and the compressed gas discharge valves 12 are coupled to the usual liquefied gas pipes. These valves communicate with ports 14 in the cylinder wall.

In order to secure transmission of the

compressed gas remaining in the ends of the cylinder while the piston is completing its stroke in either direction without necessitating the use of additional piping, a port 15 is formed at each end of the cylinder by a short shallow groove extending from the ports 14 toward the middle of the cylinder and small radial ports 16 are formed in the bosses *n*, the port 14 being extended as at 17 to effect communication with these ports 16. The dimensions of the piston *e* and the axial length of the port formed by 14, 15 and 17 are such that the piston will uncover the ports 15 just before it reaches the end of its stroke thus forming a by-pass between the low pressure and high pressure sides of the piston at the end of its stroke and effecting a momentary communication through which the compressed gas will be transmitted from the high pressure to the low pressure side.

It is essential to the efficient working of the compressor that the impulse of the compressive force be exerted on the compressor during the time that the piston *e* traverses the port 15 in its return stroke and the design of valve gear I prefer to use to perform this function comprises a slide valve *k*, before mentioned, a valvular piston 20 by which the slide valve is rigidly carried through a yoke 21. This valvular piston reciprocates in cylinder 22 to which steam is admitted from any available source of steam generation by a pipe 23 which communicates with an internal circumferential port 24 surrounding the piston at the middle of the cylinder and communicating in turn with a port 25 leading into a steam chest 26. This steam chest contains the slide valve *k* and communicates with the opposite ends of the steam cylinder by ports 27 and 28 respectively, the exhaust port for the steam cylinder being indicated at 29. The slide valve is adapted to, when in one position, uncover either port 27 or 28 and effect communication between the other of these ports and exhaust port 29, the valve being reciprocated intermittently from one position to the other and it is important for the proper working of my gas compressing unit that the movement of this valve be rapid and timed precisely to operate when the transmission of compressed gas from one side of the gas piston to the other is taking place. The device I prefer to use for performing this function consists of an oscillatory valve and an operative connection therebetween and a moving part of the unit, the oscillatory valve being indicated at 30 Figs. 5, 6 and 7. It is of plug form and rotatably mounted in the valvular cylinder 22 and penetrating the same and the piston 20, the latter being slotted as at 31 and 32 to accommodate its movement. The valve case 35 is formed in the wall of the cylinder 22, and ports 36 and 37 lead from this casing to the opposite ends of

the cylinder; while a branch 39 from steam pipe 23 leads to this casing 35, and an exhaust 40 leads from the opposite side thereof. The valve has in its opposite sides a pair of ports 41 and 42 so arranged that when in one position, communication is effected between steam supply pipe 39 and one of the ports 36 and 37, while the other, 41 or 42, simultaneously effects communication between port 36 and exhaust port 40. Oscillation is imparted to the valve by the piston rods through the medium of the coupling *h* in the following manner:—

The slide rod 50 is mounted slidably in a pair of brackets 51 and 52 preferably carried by the arm *v* of the yoke, the end of the rod toward the engine being connected by the link 55 to an arm 56 rigidly secured to the stem of valve 30. A bracket 60 on the coupling rigidly carries a sleeve 61 adapted to fit slidably over the slide rod between a pair of abutment blocks 62 and 63 respectively carried by this slide rod and set rigidly thereon. These blocks are relatively placed and the relative length given to sleeve 61 are such as to cause the movement of the slide rod when the gas piston nears the end of its stroke in either direction. The throttle valve for controlling the admission of the steam to the power member of the unit is indicated at 75.

Operation.

In the operation of my gas compressing unit, when the throttle is opened the steam will flood the steam chest 26 and at the same time enter one end of the cylinder 22 and impel piston 20 toward the opposite end of this cylinder, the effect being that valve *k* will be shifted to uncover, say for instance, port 28 and connect port 27 to exhaust port 29. An impulse is thus given to the piston of the steam engine which is driven to one end of the steam cylinder *b* and simultaneously through piston rods *f* and *g* piston *e* is driven to one end of the gas cylinder *c*. As this latter piston reaches the end of its stroke, it uncovers port 15 and the compressed gas, which has not been expelled and would otherwise be trapped in the end of the cylinder and obstruct the piston and prevent the completion of its stroke, is forced back through the by-pass presented by the ports 16, 17, 14 and 15. Simultaneously with this transmission of the compressed gas the sleeve 61 engages say for instance block 62 and shifts slide rod 50 thereby turning valve 30 and reversing the flow of the steam into cylinder 22 which has the effect of practically instantaneously impelling piston 20 in its return stroke by shifting the slide valve. Steam is thus practically instantaneously admitted to the opposite side of the piston of the engine and its return stroke is commenced. This is re-

peated alternately as the gas piston approaches the ends of its strokes.

The advantages are of an important nature from a commercial, marine and naval 5 point of view; they may be stated to reside in the fact that the unit is practically fool proof. With any compressors heretofore employed, it has been a practice to use a fly-wheel to carry the piston of the compressor 10 sor to the end of the cylinder thus setting up in the piston relatively great inertia. The result was that when the compressor cylinder became flooded or charged to a more or less degree with liquefied gas which could 15 only be expelled by relatively slow process, the latter would act as a stop for the piston owing to its incompressible nature, and as the inertia of the fly-wheel was greater than the resistance of the cylinder, the latter was 20 frequently burst.

This danger is obviated in my improved unit by the fact that the steam force is of a yielding nature, as it consists only of the steam pressure in the steam engine. With 25 my unit, therefore, in the event of liquefied gas accumulating in the compression cylinder the engine will be stalled until the liquid can be expelled through the discharge port or ports of the compression cylinder, and 30 considerable relief is given and the speed and efficiency of the engine returned more quickly to normal by the provision for the transmission of the gas from the high pres-

sure side to the low pressure side at each stroke of the compressor piston, the liquefied gas being transmitted just as readily as the compressed gas. 35

One of the principal advantages of this invention is that the compressor will clear itself of obstructing liquids without stopping 40 its operation.

What I claim is as follows:

A gas compressor including a cylinder, a piston within the cylinder, inlet and discharge valves located at each end of the cylinder, the latter having a port at each end thereof effecting communication between the interior of the cylinder and the said inlet and discharge valves said cylinder having a radially extending groove in its end constituting an extension of said port and a second groove constituting an inward longitudinal extension of said port the port with extensions constituting a constantly open by-pass for effecting communication 55 between the high pressure and low pressure sides of the piston when the latter is at the ends of the cylinder.

In testimony whereof I have signed my name to this specification in the presence of 60 two witnesses.

CARL W. VOLLMANN.
